UNITED STATES PATENT OFFICE.

JOHN E. WALSH, OF NEW YORK, N. Y.

HOISTING APPARATUS.

SPECIFICATION forming part of Letters Patent No. 488,044, dated December 13, 1892.

Application filed August 24, 1892. Serial No. 443,977. (No model.)

To all whom it may concern:

Be it known that I, JOHN E. WALSH, a citizen of the United States, and a resident of New York, in the county of New York and 5 State of New York, have invented certain new and useful Improvements in Hoisting Apparatus, of which the following is a specification.

My invention relates to improvements in hoisting apparatus; and its object is to provide an automatic mechanism for the speedy return of the trolley carrying the hoisting-rope after the load has been deposited from either end of a crane, thus saving considerable time and labor.

15 In the accompanying drawings, Figure 1 is a side elevation of an apparatus showing my improvements. Fig. 2 is a front view of the same, partially in section.

Similar letters of reference designate corresponding parts in all the figures.

Although one crane or arm could be arranged with my improvements attached to it, I preferably employ two slotted arms D, one at each side of a mast A, mounted thereon by 25 means of an adjustable sleeve B, and capable of being swung up and sidewise. A trolley R, carrying the roller r², guiding the hoisting-rope h, is mounted upon each arm and free to travel thereon from one end of the 30 arm to the other. In a stirrup-shaped forging or casting C, in front of each arm D, are preferably mounted two sets of rollers r and r', one above the other, and upon the end of each arm a roller r³ is secured by means of 35 the stirrup E. Below each side of the sleeve B is secured one block of a hoisting-tackle H, and a weight w, guided in the groove a of the mast A, is suspended from the other block. The end of the guide rope or fall h' is given 40 several turns around a drum d, connected with a brake-wheel d', and in the case of loading from the dock into a vessel (represented in Fig. 1 of the drawings) the end is guided up and over a roller r to the front end of the 45 trolley R and is there secured in its proper position. The drums d d', with the brake-wheels d' d', are mounted one upon each end of a shaft f secured to the mast A, and are free to turn thereon, although the motion of 50 either one can be arrested by the depression of a treadle t, whereby a brake-band d² is thrown in contact with its respective brake-

wheel d'. As each arm is worked separately, two hoisting-engines K K are required, and in the case illustrated in Fig. 1 a hoisting-rope h, after leaving the drum k of its respective hoisting-engine, will be passed up and over a roller r' and from there to and half-way around the roller r³, and back over the pulley r², mounted in the trolley R, to the place of loading. The weight w will be selected in such a manner that it will return the trolley to its starting position when the load is delivered, an adjustable stop s checking the motion of the weight, and thereby regulating the point at which the trolley stops on its return.

The operation of one side of my hoisting apparatus is then as follows: The trolley R is held in its starting position, while the weight w is resting upon the stop s (in the case represented in Fig. 1 the starting position of the trolley will be nearest to the mast) and the load is attached to the hoisting-rope h. Before starting the hoisting motion the engineer 75 will press with one foot upon the corresponding treadle t and start the hoisting-machine and continue to hoist till the load approaches the crane D. At this moment the engineer releases his hold upon the treadle t, whereupon the trolley R will travel forward, slightly dropping the load, which at the same time will raise a weight w. The hoisting is continued without intermission during this operation. If the forward motion of the trolley or 80 the dropping of the load becomes too rapid, the foot is placed upon the treadle again, and this is repeated till the trolley arrives at its end point over a hatch of a vessel, whereupon 85 the load is lowered to the bottom of a vessel. 90 As soon as the load is detached from the hoisting-rope and also the pressure from the brake-band d² is released, the weight w will automatically return the trolley R to its starting-point, (the hoisting-rope having previously 95 been raised to a position high enough to prevent injury to attendants on the vessel.) If the load is to be taken out of a vessel and transferred to a dock, the positions of the ropes h and h' are exchanged. The rope h' 100 is then guided from the drum d over a roller r' to and half-way around the roller r³ and secured to the outer end of the trolley R, while the rope h is passed from a hoisting-drum

k over a roller r^2 in the trolley R and dropped at the opposite side of r^2 to the ground below. In this case the weight *w* will return the trolley automatically to a desired point at the 5 outer end of an arm D over the hatch of a vessel, and the load will be deposited upon a dock in the same manner as described above. As each arm is worked independently by a separate attendant, it is evident that one arm 10 can be worked loading into the hatch of a vessel, while the other unloads the vessel from another hatch, although the entire apparatus, instead of being mounted upon a dock, may be mounted upon a float, and thus 15 be made transferable.

I am aware that weights have been employed to return the trolley in one direction after the load has been deposited, and do not claim this mode of returning the trolley, broadly; but 20 What I claim, and desire to secure by Letters Patent, is—

The combination of a mast erected on a

dock or other place, arms supported thereon and adapted to be swung around in different positions, trolleys traveling upon said arms, 25 hoisting-machines for working the hoisting-ropes, tackle-ropes passing each from one end of a trolley over a pulley or pulleys to and around a drum connected with a brake and from there over the pulleys of two blocks of 30 a hoisting-tackle, to one of which blocks the other end of a tackle-rope is secured, and weights guided in the mast and suspended each from one of the blocks, while the other is secured to the mast, as and for the purposes herein shown and described. 35

Signed at New York, in the county of New York and State of New York, this 23d day of August, A. D. 1892.

JOHN E. WALSH.
